UNITED STATES PATENT OFFICE

NOAH OLIVER VINCENT, OF JOPLIN, MISSOURI

ROAD TOOL

Application filed February 2, 1929. Serial No. 337,101.

This invention relates to a road tool, and more particularly to apparatus for applying and manipulating filling material, such as tar or the like, which is used in filling the cracks of concrete roadways.

As is well known to those familiar with the art, modern concrete roads make one of two provisions for expansion and contraction thereof. The road is either subdivided in 10 process of manufacture into a series of blocks which are slightly spaced from one another and the cracks thus formed filled with tar or some other moisture-proof substance, or the road is cast in one piece and when traction 15 forms cracks therein, these cracks are filled with such a substance. In either construction, the amount of the filling employed must be sufficient to fill the crack at the time when this crack is widest or during extremely cold 20 weather, with the result that in the heat of summer, the filling is softened and by reduction of the width of the crack, caused by expansion of the road, is forced upwardly from the crack, forming at the upper surface of 25 the crack a bump which roughens the road bed and increases the liability to breakage in addition to causing discomfort to the occupants of vehicles passing thereover.

It is accordingly necessary that the excess 30 be removed at this time and then replaced. Due to the passage of vehicles thereover, this material is often spread to a considerable extent to opposite sides of the crack in the form of a thin layer which is extremely difficult to 35 work and which, by the ordinary process of removal, is rendered unfit for subsequent use. An important object of this invention is the provision of a structure for use either in providing these cracks with their original fillings 40 or in returning a dispersed filling to the crack without destroying the value of the material.

A further object of the invention is to provide a device of this character which, when used in the latter capacity, will at once move 45 the material to the crack to be filled and smooth and flatten it in the crack, so as to provide a neat appearance and a smooth roadway.

A still further object of the invention is to 50 provide a neat, readily manipulatable struc-

ture which may be handled by one man, which may be readily and cheaply manufactured, which will be durable and efficient in service, and may be modified to enable its use in situations where, in its ordinary capacity, it would 55 prove insufficient.

These and other objects I attain by the construction shown in the accompanying drawings, wherein for the purpose of illustration is shown a preferred embodiment of my invention and wherein:

Figure 1 is a side elevation of a road tool constructed in accordance with my invention;

Figure 2 is a plan view thereof, portions being broken away;

Figure 3 is an enlarged plan view of the burner and blade mounting;

Figure 4 is a transverse sectional view through the blade;

Figure 5 is a longitudinal sectional view 70 through the blade;

Figure 6 is an illustration showing a modified arrangement employed when greater heat is desired.

Referring now more particularly to the 75 drawings, the numeral 10 generally designates a preferably metallic frame, the upper end of which forms a handle 11. The side members 12 of this frame preferably converge toward their lower end and are secured 80 to a valve conduit 13 leading from a fuel supply tank 14 supported between these side members adjacent the upper end thereof. This supply tank has a suitable filling opening 15 and is preferably provided with a 85 pressure pump 16 permitting the contents thereof to be placed under pressure. The conduit 13 communicates with a transversely extending header 17, which header has arising therefrom an outlet 18 terminating in a 90 forwardly extending branch 19 which is, in turn, connected with a second transverse header 20 preferably in the form of a section of pipe.

Each header 17 and 20 has arising therefrom at its opposite ends an outlet 21, the upper end of which communicates through one branch of a T 22 with the lower end of a coil 23. The upper end of this coil is provided with a horizontal terminal 24 extend- 100

ing diametrically of the coil and having an outlet orifice 25 directed axially of the coil. The axes of the coils incline downwardly and inwardly, for a purpose presently to appear.

5 The second branch of the T 22 is provided with a removable plug 26 permitting attachment thereto of a second similar coil under certain circumstances, hereinafter more fully explained.

10 The rear header 17 has arranged therebeneath a transversely extending smoothing blade 27. This smoothing blade is in the form of a perforated plate arcuately curved in a direction transverse to the header 17 and 15 having its forward edge upwardly bent at the center to render this edge concave, as indicated at 28. The rear edge of the blade is straight and the concavity is gradually reduced toward this rear edge, so that the contacting surface of the bottom of the blade is 20 provided with a rearwardly converging groove. U-bolts 29 engaging the forward end of the conduit 13 and the forwardly extending branch leading from the header 17 25 support this blade. If desired, from the ends of the forward header 20, parallel branches 30 may be extended, having arranged thereon a longitudinally extending series of burners. These burners, as is the case of the burner 30 coils 22, will have their axes inclining downwardly and inwardly toward the center of the path of movement of the device considered as a whole.

Means are provided for detachably securing to the frame 10 below the tank 14 thereof a filling material tank 31. This tank, when employed, will be provided with an outlet conduit 32 which, in the applied position of the tank, will extend forwardly over the rear header 17 and discharge immediately in advance of the center of the blade through a downturned outlet spout 33. In the discharge line 32, a valve 34 will be disposed operated through an extension rod 35 operable 40 by a person pushing the tool. Under conditions where this tank is employed, an axle 36 is secured transversely of the lower end of the frame, which axle is provided with supporting wheels 37, so that the weight of the material in the tank will not place too great a 45 strain upon the operator.

In filling cracks by the use of apparatus of this character, the tank 31 is preferably applied to the frame and the burners placed in 50 operation. These burners will serve not only to heat the material delivered from the tank but will likewise serve to preheat the surface to which the material is to be applied, so that any moisture is removed from this surface 55 and the surface best prepared for the reception of the material. The material discharged in advance of the blade will be drawn into line with the crack by the rearwardly converging groove in the bottom of the blade and 60 smoothed by the rear edge of this blade so

that a neat finish is provided. In restoring material to old cracks, the burners are placed in operation and the heat generated thereby will soften the material lying at opposite sides of the crack so that this material may 70 be swept up by the smoothing blade and drawn into the crack and finally deposited therein.

It will be obvious that in addition to the uses above described, apparatus of this character may be very conveniently employed in thawing or drying a portion of a road bed or other surface and that the apparatus is capable of many other uses not herein mentioned.

Since the construction hereinbefore set forth is capable of a certain range of change and modification without materially departing from the spirit of the invention, I do not limit myself to such specific structure except as hereinafter claimed.

I claim:—

1. In a road tool of the character described, a smoothing blade having a straight ground engaging rear portion and a front portion concavely curved at its under surface, the concavity of the front portion of the blade gradually merging with said straight edge whereby a rearwardly converging groove is produced in the bottom of the blade, means for heating said blade, and means for propelling the blade over the road.

2. In a road tool of the character described, a smoothing blade having a straight ground engaging rear portion and a front portion concavely curved at its under surface, the concavity of the front portion of the blade gradually merging with said straight edge whereby a rearwardly converging groove is produced in the bottom of the blade, means for heating said blade, means for propelling the blade over the road, and burners disposed in advance of the blade and adapted to deliver downwardly converging blasts of flame engaging the roadway at opposite sides of a medial plane bisecting the groove.

3. In a road tool of the character described, a smoothing blade having a straight ground engaging rear portion and a front portion concavely curved at its under surface, the concavity of the front portion of the blade gradually merging with said straight edge whereby a rearwardly converging groove is produced in the bottom of the blade, means for heating said blade, means for propelling the blade over the road, and means for delivering crack filling material to the road in advance of and in alignment with the groove of the blade.

4. In a road tool of the character described, a smoothing blade having a straight ground engaging rear portion and a front portion concavely curved at its under surface, the concavity of the front portion of the blade gradually merging with said straight edge whereby a rearwardly converging groove is

produced in the bottom of the blade, means for heating said blade, means for propelling the blade over the road, burners disposed in advance of the blade and adapted to deliver 5 downwardly converging blasts of flame engaging the roadway at opposite sides of a medial plane bisecting the groove, and means for delivering crack filling material to the road in advance of and in alignment with the 10 groove of the blade.

5. In a road tool, a handle, a blade secured to the lower end of the handle and extending transversely thereof, the bottom face of the blade having a groove extending in the same 15 general direction as the handle the walls of which converge rearwardly, and means for heating the blade.

6. In a road tool, a handle, a blade secured to the lower end of the handle and extending 20 transversely thereof, the bottom face of the blade having a groove extending in the same general direction as the handle the walls of which converge rearwardly, means for heating the blade, and means for delivering crack 25 filling material to the road in advance of the blade.

7. In a road tool, a handle, a blade secured to the lower end of the handle and extending transversely thereof, the bottom face of the 30 blade having a groove extending in the same general direction as the handle the walls of which converge rearwardly, means for heating the blade, a tank secured to the lower end of the handle and having an outlet extending 35 over the blade and provided at its forward end with a downturned nozzle discharging in advance of the blade and in alignment with said groove, and means for controlling discharge through said outlet.

40 8. In a road tool, a handle, a blade secured to the lower end of the handle and extending transversely thereof, the bottom face of the blade having a groove extending in the same general direction as the handle the walls of 45 which converge rearwardly, means for heating the blade, and burners arranged in advance of and at opposite sides of the center of the blade, said burners delivering blasts of flame which converge downwardly and engage the road in spaced relation to one another.

9. In a road tool, a handle, a blade secured to the lower end of the handle and extending transversely thereof, the bottom face of the 55 blade having a groove extending in the same general direction as the handle the walls of which converge rearwardly, means for heating the blade, means for delivering crack filling material to the road in advance of the blade, and burners arranged in advance of and at opposite sides of the center of the 60 blade, said burners delivering blasts of flame which converge downwardly and engage the road in spaced relation to one another.

65 10. In a road tool, a handle, a blade secured

to the lower end of the handle and extending transversely thereof, the bottom face of the blade having a groove extending in the same general direction as the handle the walls of which converge rearwardly, means for heating the blade, a tank secured to the lower end of the handle and having an outlet extending over the blade and provided at its forward end with a downturned nozzle discharging in advance of the blade and in alignment with 70 said groove, means for controlling discharge through said outlet, and burners arranged in advance of and at opposite sides of the center of the blade, said burners delivering blasts of flame which converge downwardly 75 and engage the road in spaced relation to one another.

In testimony whereof I hereunto affix my signature.
